US00D948131S

(12) **United States Design Patent** (10) **Patent No.:** **US D948,131 S**
(45) **Date of Patent:** **** Apr. 5, 2022**

(54) **HEADGEAR OF HELMET**

(71) Applicant: **Lincoln Global, Inc.**, Santa Fe Springs, CA (US)

(72) Inventors: **Paul H. Rumpke**, Cleveland, OH (US); **Chase P. Rutt**, Cleveland, OH (US); **Richard D. Smith**, Hudson, OH (US); **Ziqian Wu**, Nanjing Jiangsu (CN)

(73) Assignee: **LINCOLN GLOBAL, INC.**, Santa Fe Springs, CA (US)

(**) Term: **15 Years**

(21) Appl. No.: **29/692,598**

(22) Filed: **May 28, 2019**

(51) LOC (13) Cl. **02-03**

(52) U.S. Cl.

USPC **D29/122**

(57) **CLAIM**

The ornamental design for a headgear of a helmet, as shown and described.

DESCRIPTION

FIG. 1 is a perspective view of the design for the headgear of a helmet;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The evenly spaced broken lines in the drawings illustrate portions of the headgear of a helmet and form no part of the claimed design.

1 Claim, 7 Drawing Sheets
